UNITED STATES PATENT OFFICE.

ERNST J. GUENZEL, OF MILWAUKEE, WISCONSIN.

OVERCOAT.

1,163,909.

Specification of Letters Patent.

Patented Dec. 14, 1915.

Application filed December 14, 1914. Serial No. 877,013.

to all whom it may concern:

Be it known that I, ERNST J. GUENZEL, a citizen of the United States, residing at Milwaukee, county of Milwaukee, and State of Wisconsin, have invented new and useful Improvements in Overcoats, of which the following is a specification.

My invention relates to improvements in overcoats.

10 The object of my invention is to provide such coats with muffling attachments, adapted to protect the chest and throat of the user when in use, and which, when not in use, may be folded to a concealed position, where 15 they will not affect either the appearance or the fit of the garment to which they are applied.

In the drawings Figure 1 illustrates an overcoat embodying my invention, showing 20 the same in use with the muffling attachments folded, their position being indicated by dotted lines. Fig. 2 is a similar view, showing the muffling attachments extended to the position of use. Fig. 3 is a perspective view of the coat, showing the attachments in folded position. Fig. 4 is a similar view, showing a modified form of construction.

Like parts are identified by the same reference characters throughout the several views.

The outer coat or overcoat A may be of any ordinary type, except that it has a pair of flaps B secured to the facings C of the 35 coat, each flap being preferably stitched to the facing C along one margin D. The upper end of the flap terminates substantially at the shoulder adjacent to the junction of the facing C with the collar E. The flap has 40 a curved marginal portion F, which is adapted to serve as an extension of the collar E, when the flap is in an unfolded position of use. The two flaps are similar in contour and are of a generally triangular 45 form, and they are of sufficient size so that they will partially overlap upon the chest and throat of the user, the apex b of one flap underlying the apex b' of the other flap when the two flaps are folded together. The 50 apex portion b' of the outer flap is provided with a button or other suitable fastening member G, adapted to engage a button hole or counterpart fastening member H, which is preferably located near the 55 middle of the marginal portion F. From

the apex b (or b'), the free edge marginal portion I of each flap extends downwardly and convergently to the lower end of the margin D.

When not in use, the flaps are folded inwardly, as shown in Fig. 3, with the free apexes b, b', extending in the direction of the arm holes. The flaps are preferably laid flat upon the inner face of the coat in the folded position and stitched to the coat while 60 in this position, so that they will fit snugly to the inner face of the garment when folded, without producing wrinkles or otherwise causing discomfort to the wearer and without injuring the appearance of the coat. 65 When extended to the position of use, the flaps will of course be folded or doubled upon themselves across the stitching line, in order that they may be brought intolapping positions upon the chest and throat. 70 I do not, however, limit the scope of my invention to any specific form of connection 75 between the flap and the facing of the coat.

In the modified form of construction shown in Fig. 4, the flaps are connected 80 with each other by a neck band J, whereby when the flaps are in the unfolded position of use, the neck band J will form an extension of the collar in the rear. In Fig. 85 4 I have also shown a slit K formed in the facing C of the coat into which the free apex b of the flap may be inserted. This feature is of course applicable, if desired, to the form of construction shown in Figs. 1, 2 and 3.

While I have described my invention with particular reference to overcoats, it will of course be understood that it is applicable to any form of coat worn by either sex.

I claim—

The combination with a coat, of a pair of flaps each comprising an independent piece of cloth, of a generally triangular form arranged with an upper apex substantially at the end of the collar stand and one margin extending downwardly along the facing adjacent to the lapel to a lower apex, and with a third apex normally projecting outwardly in the direction of the adjacent arm pit, said margin being stitched to the facing 100 with the normally concealed face resting in a flat position upon said facing, and said flap being adapted to be swung outwardly 105 to carry its free apex across the throat of the wearer with the connected marginal 110

portion folded over the line of stitching,
said flaps having fastening members adapt-
ed for mutual engagement when swung
across the throat, whereby the flaps are
5 adapted to be connected with each other in
an over-lapping position, substantially as
described.

In testimony whereof I affix my signature
in the presence of two witnesses.

ERNST J. GUENZEL.
